CLAIM

The ornamental design for a printer, as shown and described.

DESCRIPTION

FIG. 1 is a front, top, and right side perspective view of a printer showing our new design;
FIG. 2 is a rear, top, and left side perspective view thereof;
FIG. 3 is a front view thereof;
FIG. 4 is a rear view thereof;
FIG. 5 is a top plan view thereof;
FIG. 6 is a bottom plan view thereof;
FIG. 7 is a right side view thereof; and,
FIG. 8 is a left side view thereof.
The features shown in broken lines in the drawings depict environmental subject matter only and form no part of the claimed design.
